William H. McDonough, Inventor
By his Attorney, Samuel G. Darby

UNITED STATES PATENT OFFICE.

WILLIAM H. McDONOUGH, OF NEW YORK, N. Y., ASSIGNOR, BY MESNE ASSIGNMENTS, TO THE AMERICAN BRAKE SHOE AND FOUNDRY COMPANY, OF WILMINGTON, DELAWARE, A CORPORATION OF DELAWARE.

COMBINED REINFORCING-PLATE AND KEY-LUG FOR BRAKE-SHOES.

1,226,545.

Specification of Letters Patent.

Patented May 15, 1917.

Original application filed April 25, 1916, Serial No. 93,362. Divided and this application filed September 29, 1916. Serial No. 122,801.

To all whom it may concern:

Be it known that I, WILLIAM H. McDONOUGH, a citizen of the United States, residing at New York, in the county and State of New York, have made a certain new and useful Invention in Combined Reinforcing-Plates and Key-Lugs for Brake-Shoes, of which the following is a specification.

10 The invention relates to brake shoes and particularly to the reinforcing back plate and key lug employed in connection with such devices, the present application being divided from my copending application 15 Serial Number 93,362, filed April 25, 1916.

The object of the invention is to provide an integral key lug and back plate for brake shoes, and means to reinforce the structure at the point where the key lug is formed.

20 Other objects of the invention will appear more fully hereinafter.

The invention consists substantially in the construction, combination, location and relative arrangement of parts, all as will be 25 more fully hereinafter set forth, as shown by the accompanying drawing, and finally pointed out in the appended claims.

Figure 1 is a plan view of a combined 30 brake shoe back and key lug embodying my invention.

Fig. 2 is a sectional view of the same taken on the line 2—2—Fig. 1.

Fig. 3 is a similar view of a modified arrangement embodying my invention.

35 The same part is designated by the same reference numeral wherever it occurs throughout the several views.

It is a common practice in the manufacture of brake shoes to apply a reinforcing 40 back plate of ductile metal, such as sheet steel, to the cast metal shoe body, and to form a key lug for attaching the shoe to the brake head by transversely bending the back plate centrally into an integral loop with 45 openings through the transversely extending walls of the loop for the passage of the securing key. Such structure, however, interrupts the continuity of the back plate, leaving the space across the throat of the 50 integral key lug unprotected and without reinforcement. As the greatest strains, in use, are imposed on the device at the key lug, it will be seen that in the construction

referred to, and without reinforcement of the back plate across the throat of the key 55 lug, the weakest part of the structure occurs at the point where the greatest strains occur, and this is most undesirable in devices of this nature.

It is among the special purposes of my 60 present invention to provide a structure of back plate formed with an integral key lug, and wherein reinforcement is provided across the throat of the key lug, and in a most simple and efficient manner, thereby 65 avoiding the objections noted and securing added strength at the point where the greatest strains occur.

In the drawings, I have shown an embodiment of my invention wherein 5 designates the metal back plate, which, if desired, may be provided with the usual openings 6, therethrough to permit the metal of the cast shoe (not shown) to flush therethrough, in casting the shoe, to afford means for attaching the plate and shoe body together. Centrally of its length the plate is transversely folded or bent to form the integral key lug 7, the transverse walls 8, 9, of which having alined openings 10, formed through the 75 metal thereof for the passage of the brake head locking key. In this arrangement of 80 key slots or openings it will be seen that the entire bearing of the key is taken by the metal of the key lug itself, and this is a 85 practical advantage as it secures strength, the strains being transmitted directly to the key through the key lug.

In one form of my invention, as shown in 90 Figs. 1 and 2, the back plate 5 is pressed outwardly, at the lateral or side edges of the key lug, into transversely extending off-sets or seats 11. Into these off-sets or seats are received the ends 14 of a reinforcing tie plate, which extends across the throat of the 95 key lug and ties together the parts of the plate lying on opposite sides of the key lug. By pressing the off-sets or seats 11 in the plate on opposite sides of the key lug, and positioning the reinforcing tie plate 100 therein, the inner surface of said tie plate is brought into flush relation with respect to the inner surface of the back plate. This reinforcing tie plate may have one or more openings 16 therethrough for the metal of 105 the cast shoe body to flush through in cast-

ing the same to afford means for attaching the tie plate to the shoe body.

To reinforce the key lug, at the point of its lateral bend to form the walls thereof, 5 the tie plate 14, is centrally pressed outwardly and partially into the throat of the key lug 7. The top wall 15 of the tie plate is accordingly located well within the throat of the key lug.

10 In Fig. 3 I have shown my invention as applied to a back plate generally the same as hereinbefore described, but without the offsets or seats 11. It will be understood that the reinforcing tie plate may be 15 secured to the back plate, if desired, and in any desired manner.

Having now set forth the objects and nature of my invention, and having shown and described various forms of embodiment 20 thereof, what I claim as new and useful, and of my own invention, and desire to secure by Letters Patent, is,—

1. A back plate for brake shoes bent up transversely to form an integral key lug, 25 said plate having outwardly pressed portions adjacent the sides of said lug, to form

seats on its inner surface, and a tie plate received in said seats and spanning the throat of said lug, said tie plate having a portion thereof extending into the throat 30 of the lug.

2. A back plate for brake shoes bent up transversely to form an integral key lug, 35 said plate having outwardly pressed portions adjacent the sides of said lug, to form seats on its inner surface, and a tie plate received in said seats and spanning the throat of said lug, said tie plate having a central extension pressed outwardly from the body thereof and extending into the 40 throat of said lug.

3. A back plate for brake shoes bent up transversely to form an integral key lug, a reinforcing plate extending across the throat of said lug, said reinforcing plate having a 45 central extension pressed outwardly from the body thereof and extending into the throat of said lug.

In testimony whereof I have hereunto set my hand on this 25th day of September, 50 A. D. 1916.

WILLIAM H. McDONOUGH.
